X-RAY SPECTRAL ANALYSIS

Joshua Ladell, Flushing, and Nathan Spielberg, Hartsdale, N.Y., assignors to North American Philips Company, Inc., New York, N.Y., a corporation of Delaware

Filed June 13, 1960, Ser. No. 35,635
6 Claims. (Cl. 250—51.5)

Our invention relates to analysis of materials by X-rays and in particular to a method and apparatus for the spectrochemical analysis of materials by X-rays.

In apparatus for fluorescent X-ray chemical analysis, it is desirable that the recorded spectra be as simple as possible, consistent with the spectrum of the specimen being analyzed. Unfortunately, however, the dispersing crystals employed inevitably contain numerous sets of crystallographic planes, and these give rise to extra reflections, the most commonly recognized of which are the higher order of reflections arising from planes whose normals are colinear with the normal to the principal planes. In addition to these, however, there may be reflections from planes whose normals are slightly tilted with respect to the normal to the principal diffracting planes.

Extra reflections due to planes with tilted normals give rise to possible misidentification of the observed spectra, or if correctly identified, lead to spectral interferences which raise the minimum detectable limit of the instrument.

It is a principal object of our invention to substantially eliminate extra reflections due to planes with tilted normals from the dispersing crystal used in X-ray spectrochemical analysis and thereby improve the recorded spectra from a specimen being analyzed by X-rays.

It is a further object of our invention to simplify the identification of the observed spectra of a spectrochemical analysis by suppressing or eliminating extra reflections.

It is a still further object of our invention to increase the sensitivity of a conventional X-ray spectrograph.

It is another object of our invention to permit increase of the relative intensity of principal reflections from the analyzing crystal of an X-ray spectrograph through the use of larger angular divergence parameters but with the suppression or elimination of extra reflections which will indirectly occur and which would lead to spectral interferences.

These and further objects of our invention will appear as the specification progresses.

In accordance with our invention, we have found that extra reflections due to planes with tilted normals can be suppressed or eliminated by choice of the reflecting crystal, proper orientation of the reflecting crystal, or by appropriate collimation in the lateral plane, or any combination of these features.

The invention will be described in connection with the accompanying drawing in which:

FIGS. 1a and 1b show, respectively, an elevational (equatorial plane of diffraction) and a plan (lateral plane of diffraction) view of an X-ray spectrograph and its geometry;

FIG. 2 shows schematically the detecting volume in the equatorial plane of the spectrograph;

FIG. 3a shows schematically the detecting volume in the lateral plane;

FIG. 3b shows the locus of the center O of the detecting volume in the equatorial plane; and

FIGS. 4a, 4b, 4c and 4d show recorded spectra obtained with a spectrograph using the invention compared with a spectrograph not using the invention.

In FIG. 1, X-rays generated by an X-ray tube 1 are incident upon a specimen 2 and generate characteristic fluorescent X-rays from an element within the specimen

2

whose absorption edge is longer than the shortest wavelength of X-rays incident upon the specimen. The fluorescent X-rays are incident upon a crystal 3 adapted to rotate about an axis O. X-rays of different wave-lengths are reflected at different angles by the crystal 3, some of which enter a detector 4 mounted for rotation on a circular arc 5, at twice the angular speed of rotation of crystal 3. Divergence limiting slits 6 are provided between the specimen and the crystal as well as divergence limiting slits 7 between the crystal and the detector.

The reason for the appearances of lines which are attributable to extra reflections due to planes with tilted normals can best be understood from a consideration of the geometry of the instrument as shown in FIGS. 1a and 1b, and the following explanation.

Crystal on the crystal at O is diffracted in a direction

The central ray s_0 from the specimen incident on the crystal at O is diffracted in a direction denoted by the

unit vector s making an angle Y with s_0 , thus

$$Y = \cos^{-1}(s \cdot s_0) \quad (1)$$

Because of the extended size of the source and crystal,

the rays incident on the crystal can deviate from s_0 up to a maximum amount of $\pm \frac{1}{2}\alpha_1$ in the equatorial plane and up to a maximum amount of $\pm \frac{1}{2}\beta_1$ in the lateral plane of incidence. Similarly, because of the extended size of the crystal and detector, the rays scattered into the detector can deviate by a maximum amount $\pm \frac{1}{2}\alpha_2$ in the equatorial plane and $\pm \frac{1}{2}\beta_2$ in the lateral plane of diffraction. α_1 , α_2 , β_1 , and β_2 are controlled by the limiting slits 6 and 7 shown in FIGS. 1a and 1b.

In order to show what occurs when an X-ray is incident upon the dispersing crystal, we introduce the concept of the reciprocal lattice (cf. Buerger, X-ray Crystallography, p. 107).

The reciprocal lattice of the crystal analyzer is defined as the totality of points $r^*(h_1h_2h_3)$ given by

$$\vec{r}^*(h_1h_2h_3) = (\vec{h}_1\vec{a}_1^* + \vec{h}_2\vec{a}_2^* + \vec{h}_3\vec{a}_3^*) \quad (2)$$

where $h_1h_2h_3$ are the Miller indices and $\vec{a}_1^*$, $\vec{a}_2^*$, $\vec{a}_3^*$ the reciprocal lattice vectors related to the unit cell translations of the analyzing crystal a_1 , a_2 , a_3 by the definition

$$\vec{a}_1^* = \frac{\vec{a}_2 \times \vec{a}_3}{[\vec{a}_1 \vec{a}_2 \vec{a}_3]} \quad (3)$$

³ Cyclic permutation of $\vec{a}_2$ and $\vec{a}_3$.
If the X-rays of wave-length λ are incident upon the

crystal along the direction s_0 , the locus of points

$$\vec{r}^*(h_1h_2h_3)$$

in reciprocal space satisfying the equation

$$1 = (\lambda \vec{r}^*(\xi, \eta, \zeta) + \vec{s}_0)^2 \quad (4)$$

is designated the Ewald sphere of reflection. Diffraction from a given set of crystallographic planes ($h_1h_2h_3$) takes place in the direction s whenever the vector $\vec{r}^*(h_1h_2h_3)$ satisfies Equation 4; the direction of diffraction is given by

$$\vec{s} = \lambda \vec{r}^*(h_1h_2h_3) + \vec{s}_0 \quad (5)$$

In the most commonly used arrangements for X-ray spectrochemical analysis, the detector rotates at twice the angular speed of the crystal. In reciprocal space, this means that $\vec{s}_0$ rotates in synchronism with the crystal,

about the origin of the reciprocal lattice, and the terminus of $\vec{s}$ moves along a straight line which passes through the origin and at least one point of the reciprocal lattice.

The locus of points satisfying (4) is a sphere of radius $1/\lambda$. It is more convenient, however, in considering conventional spectrographic instruments to have the "sphere of reflection" of unit radius, since a sphere of reflection of unit radius, applicable to all wave-lengths emanating from the specimen, can then be considered as an integral part of the instrument. This can be easily accomplished by regarding the locus of points $\vec{r}=\vec{r}^*$ satisfying the equation

$$1 = \vec{r} + \vec{s}_0)^2 \quad (6)$$

as the unit sphere of reflection associated with central ray $\vec{s}_0$.

For each ray in the cone incident on the crystal, there corresponds a unit sphere of reflection. The assemblage of these spheres, which have a common point at the origin of reciprocal space, forms a solid shell-like figure.

We shall designate this solid figure as the lunoid of reflection, since any section through it will generate a pair of lunes. The center of the Ewald sphere associated with

the central ray $\vec{s}_0$ shall be considered as the center of the lunoid, and any point within the shell can be described in terms of the values of α_1 and β_1 of the incident ray whose associated Ewald sphere passes through the point. Therefore, if a reciprocal lattice point lies within the lunoid of reflection, the Laue condition is satisfied and diffraction can take place in the direction $\vec{s}$ obtained by drawing a unit vector along the line joining the center of the proper Ewald sphere to the reciprocal lattice point. The diffracted rays will be recorded, however, only if they enter a detector. Because of the limiting apertures the detector can receive only those diffracted rays which have directions within

$$\pm \frac{\alpha_2}{2} \text{ and } \pm \frac{\beta_2}{2}$$

of the unit vector $\vec{s}$ associated with the central ray $\vec{s}_0$. This is shown schematically in FIG. 2 in two dimensions. Only those reciprocal lattice points lying within the area ABCD will be detected. In three dimensions, the area ABCD becomes a volume in reciprocal space, which shall be designated as the detecting volume. As the crystal is rotated, the detecting volume then sweeps out a volume in reciprocal space, and all reciprocal lattice points lying within this swept-out volume will be recorded.

In general, the shape and position of the detecting volume depends in a complicated way upon the divergences of the incident beam, and the angle Y corresponding to the instantaneous position of the detector. Using the concept of the detecting volume, it is possible to ascertain under what conditions extra reflections will be manifest, and what measures may be taken to avoid these extra reflections.

As with the intensities of normal reflections, the intensity of extra reflections when they are manifest depends markedly upon the physical dimensions of the crystal, fluorescent source, cross-section of the detector and linear separation of these elements, in addition to the angular divergences which determine the detecting volume, cf. Spielberg, Parrish and Lowitzsch, Spectrochim. Acta 3, 564-583 (1959).

If the divergences α_1 and α_2 are small, which is the usual case in conventional spectrochemical analysis systems, extra reflections due to reciprocal lattice points in the plane of diffraction are not intercepted by the detecting volume since the width of the detecting volume in this

plane is usually sufficiently small. Thus, it can be seen in FIG. 2 that if α_1 and α_2 are negligibly small, the area ABCD becomes very small.

FIG. 3a shows a cross-section through the lunoid of reflection in the lateral plane of diffraction taken for convenience at $Y=0$, where again α_1 , α_2 are negligibly small, but β_1 , β_2 are not small. In this cross-section, the detecting volume is shown as a bifoliate figure. The maximum dimension of this figure projected on the line BOC is

$$2 \left(\sin \frac{\beta_1}{2} + \sin \frac{\beta_2}{2} \right)$$

As the detector scans in the 2:1 manner, the center of the detecting volume (which corresponds to the end point of

$\vec{s}$) moves along the line OA in FIG. 3b as already described. The detecting volume, and in particular its projection onto the plane containing OA and BOC, will change shape somewhat as scanning proceeds; however, the length of the detecting volume parallel to BOC will not change. Therefore, the projection of the swept-out volume on the plane containing OA and BC will be a rectangle of dimensions

$$2 \times 2 \left(\sin \frac{\beta_1}{2} + \sin \frac{\beta_2}{2} \right)$$

centered about the line OA. Any reciprocal lattice points that lie within this rectangle will be detected and recorded. Strictly speaking only those points lying within the trace rather than the projection of the detecting volume will be detected and recorded. Those points lying on the line OA correspond to the principal planes and higher orders thereof, whereas those points lying off the line OA correspond to the extra reflections from the planes with tilted normals.

Because the occurrence of extra reflections depends upon the incident wave-length, the spectrometer geometry, and the size and orientation of the reciprocal lattice cell of the monochromator crystal, the manifestation of extra reflections can be predicted when these factors are known.

Let p^* be the distance from the line of reciprocal lattice points being scanned (OA in FIG. 3b) to the closest point off the line. If

$$\lambda p^* < \left(\sin \frac{\beta_1}{2} + \sin \frac{\beta_2}{2} \right)$$

extra reflections will occur. (To be sure, some of these extra reflections may be of such weak intensity as to be undetectable.) To suppress or eliminate these extra reflections, the parameters p^* , β_1 and β_2 are chosen so that

$$\lambda p^* > \left(\sin \frac{\beta_1}{2} + \sin \frac{\beta_2}{2} \right)$$

p^* can be controlled by appropriate choice of crystal and/or orientation of the crystal. By choice of the crystal, we mean a crystal having as low a density as possible of reciprocal lattice points in the directions encompassed by the detecting volume, i.e., for the case cited, in the direction normal to the plane of diffraction. Such a choice is possible by considering the space group and the reciprocal lattice dimensions of the crystal selected. For a given crystal, since reflection from the principal planes will be undimensioned when the crystal is rotated about the normal to the principal planes, the crystal can be oriented to maximize the value of p^* . For a given crystal, oriented for a fixed p^* , the inequality

$$\lambda p^* > \left(\sin \frac{\beta_1}{2} + \sin \frac{\beta_2}{2} \right)$$

can be maintained by decreasing the angular divergences β_1 and/or β_2 by the use of sets of parallel foils, collimating slits, or tubes. Since such collimation results in a reduction in intensity (for the principal planes), adjustability of the collimation can be provided conditioned by the minimum value of λ to be encountered in the spectrochemical analysis. Conversely, if the value of λp^* is

sufficiently large, the values of β_1 and/or β_2 may be increased thereby increasing the intensity of reflections from the principal planes without encountering extra reflections.

FIGS. 4a, b, c and d illustrate these principles. In FIGS. 4a and 4b, a quartz crystal has been used, the principal planes (20.3) reflect at a *d*-spacing of 1.37 Å. In FIGS. 4c and 4d, a topaz crystal has been used, the principal planes (303) with a *d*-spacing of 1.36 Å. All charts show principally the BaK spectrum, $\lambda=0.33-0.39$ Å., in addition to a trace of strontium (0.8 Å.). Extra reflections are seen in FIGS. 4a and 4c. The extra reflections apparent in FIG. 4a have been suppressed as shown in FIG. 4b by rotating the quartz crystal from its orientation in FIG. 4a by 90° to a new orientation. In so doing, the value of p^* has been increased from 0.06 Å.⁻¹ to 0.41 Å.⁻¹.

In FIGS. 4c and 4d, the suppression of extra reflections (FIG. 4d) has been accomplished by reducing the value

$$\left(\sin \frac{\beta_1}{2} + \sin \frac{\beta_2}{2} \right)$$

from 0.50 to 0.10 by reduction of β_1 and β_2 , i.e., by introducing collimation before and after the crystal. By comparing FIGS. 4c and 4d, it will be seen that the intensity of the principal reflections is smaller for FIG. 4d than for FIG. 4c. In selecting crystals of this *d*-spacing on the basis of reflectivity of principal planes, the relative intensity between FIGS. 4b and 4c would normally be the controlling factor. However, it is seen that by comparing FIG. 4d with FIG. 4b, that the superior reflectivity of topaz is almost completely nullified. By extension of the principles stated here, the lateral apertures used in FIG. 4b can be made larger without introducing the extra reflections and thereby the reflectivity of the quartz be made comparable or superior to the topaz since the best value of p^* for topaz (303) is less than the best values of p^* for quartz (20.3).

It will thus be seen that a proper choice of crystal, orientation of the crystal, or additional collimation, or a combination of any of these features, results in elimination or suppression of the extra reflections which might lead to possible misidentification of elements in the specimen, or materially reduce the sensitivity of the instrument. The choice of the particular expedient will be dictated by the choice of crystals available to the operator. Thus, for a given crystal such as topaz, additional collimation may be required. If a quartz crystal is available, a preferred orientation will result in the suppression or elimination of the extra reflections. If other crystals are available, a judicious selection may suffice to minimize these extra reflections. In any event, the invention affords a choice of expedients for suppressing or eliminating these extra reflections thereby simplifying identification of elements in the specimen and increasing the sensitivity of the instrument.

While we have described our invention with reference to specific embodiments, other modifications thereof will be apparent to those skilled in the art. Accordingly, we do not wish to be limited to those embodiments since the invention is defined in the appended claims which should be construed as broadly as possible.

What we claim is:

1. In the method of analyzing a material for constituent elements thereof including the steps of exposing a specimen of said material to a beam of X-rays of a wave-length which excites the fluorescent X-ray spectrum of at least one of the elements of said specimen, monochromatizing a beam of said fluorescent radiation by reflection from a surface of a reflecting crystal, and measuring the intensity of the reflected beam, the step of suppressing extra reflections from planes of the monochromatizing crystal whose normals are tilted with re-

spect to the principal diffracting planes of the crystal by making

$$\lambda p^* > \left(\sin \frac{\beta_1}{2} + \sin \frac{\beta_2}{2} \right)$$

5 where p^* is the distance from the line of reciprocal lattice points being scanned to the closest point off the line, and β_1 and β_2 are angles of divergence of the beam incident on and reflected by the crystal in the lateral plane of diffraction, respectively.

10 2. In the method of analyzing a material for constituent elements thereof including the steps of exposing a specimen of said material to a beam of X-rays of a wave-length which excites the fluorescent X-ray spectrum of at least one of the elements of said specimen, monochromatizing a beam of said fluorescent radiation by reflection from a surface of a reflecting crystal, and measuring the intensity of the reflected beam, the step of suppressing extra reflections from planes of the monochromatizing crystal whose normals are tilted with respect to the principal diffracting planes of the crystal by selecting a crystal such that

$$\lambda p^* > \left(\sin \frac{\beta_1}{2} + \sin \frac{\beta_2}{2} \right)$$

25 30 where p^* is the distance from the line of reciprocal lattice points being scanned to the closest point off the line, and β_1 and β_2 are angles of divergence of the beam incident on and reflected by the crystal in the lateral plane of diffraction, respectively.

35 35 3. In the method of analyzing a material for constituent elements thereof including the steps of exposing a specimen of said material to a beam of X-rays of a wave-length which excites the fluorescent X-ray spectrum of at least one of the elements of said specimen, monochromatizing a beam of said fluorescent radiation by reflection from a surface of a reflecting crystal, and measuring the intensity of the reflected beam, the step of suppressing extra reflections from planes of the monochromatizing crystal whose normals are tilted with respect to the principal diffracting planes of the crystal by orienting the crystal so that

$$\lambda p^* > \left(\sin \frac{\beta_1}{2} + \sin \frac{\beta_2}{2} \right)$$

40 45 where p^* is the distance from the line of reciprocal lattice points being scanned to the closest point off the line, and β_1 and β_2 are angles of divergence of the beam incident on and reflected by the crystal in the lateral plane of diffraction, respectively.

50 55 4. In the method of analyzing a material for constituent elements thereof including the steps of exposing a specimen of said material to a beam of X-rays of a wave-length which excites the fluorescent X-ray spectrum of at least one of the elements of said specimen, monochromatizing a beam of said fluorescent radiation by reflection from a surface of a reflecting crystal, and measuring the intensity of the reflected beam, the step of suppressing extra reflections from planes of the monochromatizing crystal whose normals are tilted with respect to the principal diffracting planes of the crystal by decreasing the angles of divergence of the incident and reflected beams such that

$$\lambda p^* > \left(\sin \frac{\beta_1}{2} + \sin \frac{\beta_2}{2} \right)$$

60 65 70 where p^* is the distance from the line of reciprocal lattice points being scanned to the closest point off the line, and β_1 and β_2 are angles of divergence of the beam incident on and reflected by the crystal in the lateral plane of diffraction, respectively.

75 75 5. In the method of analyzing a material for constituent elements thereof including the steps of exposing a specimen of said material to a beam of X-rays of a wave-length which excites the fluorescent X-ray spec-

trum of at least one of the elements of said specimen, monochromatizing a beam of said fluorescent radiation by reflection from a surface of a reflecting crystal, and measuring the intensity of the reflected beam, the step of suppressing extra reflections from planes of the monochromatizing crystal whose normals are tilted with respect to the principal diffracting planes of the crystal by decreasing at least one of the angles of divergence of the incident and reflected beams such that

$$\lambda p^* \left(\sin \frac{\beta_1}{2} + \sin \frac{\beta_2}{2} \right)$$

where p^* is the distance from the line of reciprocal lattice points being scanned to the closest point off the line, and β_1 and β_2 are angles of divergence of the beam incident on and reflected by the crystal in the lateral plane of diffraction, respectively.

6. In the method of analyzing a material for constituent elements thereof including the steps of exposing a specimen of said material to a beam of X-rays of a wave-length which excites the fluorescent X-ray spectrum of at least one of the elements of said specimen, monochromatizing a beam of said fluorescent radiation by reflection from a surface of a reflecting crystal, and measuring the intensity of the reflected beam, the step

10
15

5 of increasing the intensity without introducing extra reflections from planes of the monochromatizing crystal whose normals are tilted with respect to the principal diffracting planes of the crystal by increasing the divergence of the incident and reflected beams in the lateral plane such that a maximum value p^* , given by

$$\lambda p^* > \left(\sin \frac{\beta_1}{2} + \sin \frac{\beta_2}{2} \right)$$

10 is obtained where p^* is the distance from the line of reciprocal lattice points being scanned to the closest point off the line, and β_1 and β_2 are angles of divergence of the beam incident on and reflected by the crystal, respectively.
